APPARATUS FOR RAISING LOADED
CONTAINERSBenjamin F. Fitch, Greenwich, Conn., assignor to
Motor Terminals Company, New York, N. Y.,
a corporation of Delaware

Application July 30, 1932, Serial No. 626,457

18 Claims. (Cl. 294—67)

The handling of package freight by means of demountable bodies adapted to be lifted from a highway truck onto a railroad car and vice versa, has been demonstrated as very efficient when 5 the lifting is properly effected. To lift the bodies and still retain them level, irrespective of the distribution of the load therein, I have heretofore provided hoisting mechanism having four depending cables arranged at the four corners of 10 a horizontal rectangle, so that two of the cables may connect with attaching devices on the demountable body on one side a suitable distance from the ends thereof and two with similar spaced attaching devices on the other side. 15 Then if the cables are all pulled up as a unit, the body will remain level.

Sometimes it is desirable to raise a body where such four-point lifting mechanism is not available, and in that case a locomotive crane, or 20 single hook travelling crane, carrying a suitable sling or cradle may be employed, but heretofore such lifting means has had the decided disadvantage, that, if the body were unevenly loaded, the heavier end would sag, thus causing the body 25 to engage at one end only when deposited, with danger of injury to the truck or car, and presenting difficulty in its proper placement. Moreover, if the uneven loading were extreme enough, the sagging at one end would be sufficient to 30 cause the lighter package freight to slide down toward the heavier end, injuring the contents and making the heavier end sag still more.

It is the object of this invention to provide a 35 system of handling demountable bodies from a single raising hook which will maintain the body level notwithstanding uneven loading. I accomplish this by providing an equalizing cradle suspensible from a single point and equipped with means for engaging the body at four points, 40 two on each side, there being means for shifting the cradle longitudinally of the body and with reference to the support, to compensate for the unequal loading of the body. I may thus maintain the body level and efficiently transfer it 45 from one vehicle to another, irrespective of the weight conditions within the body.

Two embodiments of a mechanism for carrying out my method are illustrated in the drawings hereof; both of them, and other modifications or equivalents, not shown, are included within my invention as summarized in the 50 claims.

In the drawings, Fig. 1 is a side elevation of 55 one form of the equalizing cradle of my invention, shown as suspended from a single hook and

suspending an unequally loaded body above an automobile truck; Fig. 2 is an end view of the construction of Fig. 1; Fig. 3 is an enlarged end view of the cradle mechanism of Figs. 1 and 2; Fig. 4 is a vertical cross-section on the line 4—4 on Fig. 3; Fig. 5 illustrates a second embodiment of the equalizing cradle, being a vertical cross-section longitudinal of a supporting drum, which extends transversely of the body to be lifted; Fig. 6 is a vertical cross section of the embodiment of Fig. 5, as indicated by the line 6—6 on Fig. 5; Figs. 7 and 8 are diagrams illustrating the course of the cradle cables about the supporting members of Figs. 3 and 5, respectively.

As shown in Figs. 1 and 2, A indicates a highway truck and B a demountable body adapted to rest thereon. The body is shown as having doors b in its sides and b¹ in its ends, by which it may be loaded. Secured to the two sides, between doors b and the ends of the body are upwardly extending straps b² terminating in hooks b³, for engagement with the lifting device. In these figures, I have indicated in dotted lines a large load C near one end of the body and a small load C¹ near the other end. It will be 15 evident that a body so loaded, if suspended from a single point, as the hook D in the drawings, would naturally sag at the end carrying the load C. Such sagging, however, is prevented by the 20 equalizing cradle of my invention about to be 25 described.

Referring now to the cradle shown in Figs. 1 to 4, I have provided a suitable cross-beam or truss 10, provided with an eye 11, adapted to hook onto the crane hook D. Depending from the opposite ends of the cross-beam 10 are brackets 12, in which is journalled a shaft 13. On this shaft, adjacent the brackets are cable-carrying drums, shown as two double-groove sheaves 15. Mounted centrally of the cross-beam 10 is a motor 20, the armature 21 of which carries a worm 22, meshing with a worm wheel 23 on the shaft 13. This motor may accordingly turn the two sheaves 15 in one direction or the other, according to the direction of rotation of the motor, while when the motor is stationary, its worm will hold the sheaves stationary.

Extending over and secured to the sheaves 15 are the cables 30, one of which extends over and part way around the sheave from one direction 50 and lies in one groove thereof, and is attached thereto as at 31, while the other extends over the sheave in the other direction and is attached thereto as at 32. The cables 30 passing over the sheave members 15 flare therefrom di- 55

agonally downward in parallel vertical planes, with the result that the lower ends of the cables come to points which are in the four corners of a horizontal rectangle, and such ends at these 5 points are attached to a suspensible frame, which may engage the body, as about to be described.

As shown in Figs. 1, 2, and 3, the suspensible frame comprises longitudinal bars 40 and cross-bars 41, connected to make an open rectangular 10 floating frame. This floating frame carries on each side two depending shackles to engage the body hooks b^3 . For this purpose, I have shown U-shaped shackles 42, which are mounted on cross-pins 43 extending through the longitudinal 15 bars 40, adjacent the cross-bars. The longitudinal bars are provided with upstanding eyes 45, to which the lower ends of the cables are attached, these eyes being preferably directly over the shackles.

20 With the construction described, the cradle suspended from the single hoist hook D may be lowered over a supported demountable body and the shackles 42 engaged to the hooks b^3 of the body. Then when the hook D is drawn up, the 25 body will be raised. Now if such body is unequally loaded, the operator may readily compensate for this condition by shifting the floating frame with reference to the supporting beam 19, this being accomplished by rotating the motor 20 in one direction or the other. Accordingly, when 30 raising the body, if one end thereof tends to sag by reason of being loaded more heavily at that end, the attendant simply energizes the motor 20 in the direction to turn shaft 13, to pull in the 35 cables leading from the heavy loaded end, and pay out the cables toward the lighter end, the crane hook being longitudinally shifted as may be necessary. Thus, the floating frame, instead of being supported directly below the hook D, as 40 illustrated in broken lines in Fig. 1, is supported eccentrically thereof, as illustrated in full lines in that figure. When the cradle is in this position, the lifting action of the hook D is 45 transmitted to the four body hooks b^3 in proportion to the load thereon, so that the body remains level.

In actual operation, the adjustment of the cradle may be made as the lifting progresses, and without delaying the lifting operation, the attendant 50 simply controlling the motor 20 and the position of the load hook D as occasion requires. As soon as the body becomes level during the lift, he turns off the current to the motor 20 and thereafter the body is raised or lowered in a level condition.

In place of the worm and worm wheel mechanism and the two cable drums described, I may employ the single internally-driven drum illustrated in Figs. 5 and 6. In these views, the cross-beam 110 has a suspending eye 111 and depending end brackets 112, in which is journaled a cross-shaft 113. On this shaft is mounted a transverse drum 115, by internal spiders 117; the drum has near its ends grooves 116 about which loop the cables 130, leading diagonally downward to the supporting frame, as already described. In this case, I may employ at each side a single cable 130, which makes a few turns about the drum and then leads diagonally downward in the other direction, as illustrated in Fig. 8.

To rotate the drum 115 in one direction or the other and hold it in any desired position, I have shown a motor 120, carried by one of the brackets 112. The armature of this motor is 75 mounted on a sleeve 121, journaled on the shaft

113. This sleeve is formed with an eccentric portion which lies within two gears 124 and 125, which are rigid with each other. These gears are nearly alike but one of them has slightly more teeth than the other. The gear 124 meshes with a stationary internal gear 126, shown as carried by a spider 127 on the frame of the motor 120. The other gear 125 meshes with an internal gear 128 on the drum 115. 5

In the construction described, the drum is rotated in one direction or the other according to the direction of the rotation of the motor, because the turning of the armature of the motor turns the eccentric and thus gives a circular translation to the two gears 124 and 125, as a unit, but as these two gears have a different number of teeth it follows that the movable gear 128 on the drum will be crowded in one direction or the other as the gear 124 coacts with the stationary gear 126. If the gears 124 and 125 differ from each other, for instance, by one tooth, there would result a feeding of the drum only a distance corresponding to one gear tooth for each complete rotation of the motor armature. This system therefore provides a powerful gear reduction enabling the ready shifting of the support when suspending a heavily loaded body.

In the embodiment last described, as well as in the former one, the floating frame is hooked to the body and then the raising by the hoist hook 30 D may begin and the cradle be adjusted in one direction or the other, during the first part of the raising action, to compensate for the uneven loading, by rotating the motor in one direction or the other.

It is to be understood that with either embodiment of my invention, the motor is reversible, and the operator is provided with a suitable controlling switch, whereby he may suitably energize the motor for rotation in the desired direction, or hold it stationary. With either form of gear reduction shown, the device is self-locking. If it be desired to provide a gear reduction by a train of spur gears, this might be employed and a solenoid brake used to hold the armature stationary, 45 when no current is flowing. In any case, it is desirable to lock the shiftable support for the cradle cables whenever the load has been equalized and is level.

I claim:

1. In an apparatus of the character described, the combination of a beam adapted to be attached to a raising hook, a floating frame adapted to be attached to a demountable body at four points, two on each side of the body, a pair of cables connecting the floating frame with the beam, and means for shifting said cables in one direction or the other to cause the frame to be eccentric of the beam.

2. In a device of the character described, the combination of a suspensible beam, a shaft carried thereby, a sheave or drum member on the shaft, a pair of cables passing onto and off of said sheave or drum, a floating frame to which the cables are anchored, and which has means for attachment to the body, and means for turning said shaft in one direction or the other.

3. In an apparatus of the class described, the combination of a floating rectangular frame, four load engaging shackles depending from the frame, two on each side, a rotary member, means for suspending the rotary member from a single lift hook, and two cables, each anchored to the floating frame and intermediately passing about the rotary member in such manner as to be 75

moved thereby, and a motor for operating the rotary member.

4. In an apparatus of the class described, the combination of a floating rectangular frame, 5 four load engaging shackles depending from the frame, two on each side, a rotary member extending transversely of the frame, means for suspending the rotary member centrally from a single lift hook, and two cables, each anchored 10 at opposite ends to the floating frame adjacent the shackles and intermediately passing about the rotary member in such manner as to be moved thereby, a motor and gearing connecting it with the rotary member, said gearing being of a self-locking nature.

5. In a device of the character described, the combination of a suspensible member having means for attaching it to a single load lifting hook, a shaft carried by said member, a rotatable 20 drum or sheave on said shaft, a cable passing about the sheave or drum and extending diagonally downward in opposite directions therefrom, a frame to which the lower ends of the cable are attached, and which is adapted to be 25 attached to a demountable body, a motor for rotating the sheave or drum, and means for holding sheaves or drum in the position given it by the motor.

6. In a device of the character described, the combination of a suspensible beam or truss having means for attaching it to a single load lifting hook, said beam or truss having depending 30 brackets adjacent its ends, a drum rotatably mounted between the brackets, two cables passing about the drum and extending diagonally downward in opposite directions therefrom, a floating frame to which the lower ends of the cable are attached, and which is adapted to be 35 attached to a demountable body, and a motor for rotating the drum.

7. In a device of the character described, the combination of a suspensible beam or truss having means for attaching it to a single load lifting hook, said beam or truss having depending 40 brackets adjacent its ends, a shaft mounted in said brackets, a pair of sheaves on said shaft adjacent the brackets, two cables passing about the sheaves and extending diagonally downward in opposite directions therefrom, a floating frame 45 to which the lower ends of the cable are attached, and which is adapted to be attached to a demountable body, and a motor for rotating the shaft.

8. In a mechanism of the character described, the combination of a suspensible beam, a shaft carried thereby, a pair of sheaves on the shaft, cables passing about the sheaves and extending diagonally downward in opposite directions therefrom, a rectangular floating frame to which the 50 cables are attached, four shackles carried by the frame adapted to be secured to a load, a worm wheel on the shaft, and a driving motor mounted on the beam and operating a worm engaging the worm-wheel.

9. The combination of a suspensible beam, a rotary drum carried thereby, a pair of cables passing about the drum and extending diagonally downward in opposite directions therefrom, a floating frame to which the ends of the cables 55 are attached, means for attaching the frame to a demountable body at four points, two on each side, a motor carried by the cross-beam and internal gearing within the drum given by the motor and reacting against a stationary member and operating to turn the drum at a reduced 60

speed in one direction or the other according to the rotation of the motor.

10. In an apparatus of the character described, the combination of a suspensible frame having parallel spaced side bars, depending shackles carried thereby, two on each side, these shackles being adapted to engage attaching devices on a demountable body, a transverse beam having means for its attachment to a single hook hoist, means connecting the opposite ends of said beam 10 with the two side bars respectively, and mechanism for moving said connecting means to change the relation of the beam to the suspended frame.

11. The combination of a supporting device 15 having a rotary sheave, a floating frame adapted to be attached to a load, a flexible member attached to the floating frame and intermediately embracing the sheave, and means for rotating the sheave.

12. The combination of a supporting device having means for its attachment to a single hook of a lifting mechanism, a pair of rotary sheaves mounted on said supporting device, a floating frame adapted to be attached to a load, 25 a pair of flexible members attached at their ends to the floating frame and intermediately embracing the sheaves, and means for rotating the sheaves as a unit to wind in the flexible members on one side and pay them out on the other to 30 shift the suspensible frame with reference to the supporting hook.

13. The combination of a supporting device having means for its attachment to a single hook of a lifting mechanism, a rotary sheave mounted 35 on said supporting device, a floating frame having four depending shackles at the four corners of a rectangle adapted to be attached to a demountable body, a flexible member attached to the floating frame and intermediately embracing the sheave, and means for rotating the sheave to wind in the flexible member on one side and 40 pay it out on the other to shift the suspensible frame with reference to the supporting hook.

14. In a hoist frame, the combination of a 45 suspensible frame having load attaching devices, adapted to engage a body to be hoisted, a supporting device adapted to be removably connected with the single hook of a hoisting mechanism, flexible means connected to said device and 50 to said suspensible frame and means for shifting the flexible means with reference to said supporting device.

15. In a hoist frame, the combination of a 55 suspensible frame having load attaching devices, adapted to coact with corresponding members on a body to be hoisted, a supporting device adapted to be removably connected with the single hook of a hoisting mechanism, flexible means connected to said suspensible frame and 60 intermediately movably connected with said supporting device, and means for shifting the flexible means at the connection to said supporting device.

16. In a hoist frame, the combination of a 65 suspensible rectangular frame having load attaching devices, two on each side, adapted to coact with corresponding members on a body to be hoisted, a supporting device adapted to be removably connected with the single hook of a hoisting mechanism, flexible means connected at 70 its ends to said suspensible rectangular frame and intermediately movably connected with said supporting device, and means for shifting the 75

flexible means in the direction of its length with reference to said supporting device.

17. The combination of a suspensible rectangular frame having parallel side bars each carrying two load attaching devices adapted to cooperate with corresponding members on a demountable truck body, a supporting device adapted to be removably connected with the single hook of a hoisting mechanism, said supporting device being shiftably connected with said suspensible rectangular frame, and an electric motor for shifting the suspensible frame with reference to said supporting device.

18. In an apparatus of the character described, the combination of a suspensible frame, depending pivoted shackles carried thereby, two on each side, said shackles being adapted to engage hooks at the eaves of a demountable body, a device for attachment to a single hook hoist, supporting connections between said device and said frame, an electric motor, reduction gearing operated thereby, and mechanism operated by the gearing for shifting said frame with reference to said device. 5

BENJAMIN F. FITCH.
